US0D1050059S

(12) **United States Design Patent** (10) Patent No.: **US D1,050,059 S**
(45) Date of Patent: ** Nov. 5, 2024

(54) **CIRCUIT BOARD FOR COMPUTER PRINTERS**

(71) Applicant: **SEIKO EPSON CORPORATION**,
Tokyo (JP)

(72) Inventors: **Shuichi Nakano**, Suwa (JP); **Jun Sato**,
Suwa (JP); **Yasuhiko Kosugi**, Suwa (JP)

(73) Assignee: **SEIKO EPSON CORPORATION**,
Tokyo (JP)

(**) Term: **15 Years**

(21) Appl. No.: **35/518,465**

(22) Filed: **Sep. 28, 2022**

(80) **Hague Agreement Data**

Int. Filing Date: **Sep. 28, 2022**

Int. Reg. No.: **DM/226060**

Int. Reg. Date: **Sep. 28, 2022**

Int. Reg. Pub. Date: **Sep. 29, 2023**

(30) **Foreign Application Priority Data**

Jun. 17, 2022 (JP) ..... 2022-013048 D

(51) LOC (14) Cl. 13-03

(52) U.S. Cl.

USPC **D13/182**

(57) **CLAIM**

The ornamental design for a circuit board for computer printers as shown and described.

DESCRIPTION

1. Circuit board for computer printers

1.1 : Perspective

1.2 : Perspective

1.3 : Front

1.4 : Back

(Continued)

1.5 : Top

1.6 : Bottom

1.7 : Right

1.8 : Left

1 Claim, 8 Drawing Sheets
